METHOD OF COATING METAL

Carl H. H. Fessler and George J. Puchta, Cleveland, Ohio, assignors to The American Steel and Wire Company of New Jersey, a corporation of New Jersey

Application July 23, 1932, Serial No. 624,297

1 Claim. (CL 91—70)

This invention relates to a method and apparatus for protectively covering strip metal, one of the inventor's objects being to produce a durable and good looking finish. Other objects will be made apparent by the following disclosure.

Having reference to the accompanying drawings, which show by way of example a specific form of this new method and apparatus,

- 10 Figure 1 is a top plan;
- Figure 1a is a continuation of Figure 1;
- Figure 2 is a side elevation;
- Figure 2a is a continuation of Figure 2;
- Figure 3 is an enlarged cross-section of a detail shown in Figures 1a and 2a;
- 15 Figure 4 is a fragmentary enlarged cross-section of a detail shown in Figures 1a and 2a; and
- Figure 5 is an enlarged end elevation of a detail shown in Figures 1 and 2.
- 20 The invention is particularly applicable to coating flat strip steel or other shapes with varnish or lacquer compounds.

In detail, metal strip, generally indicated by the arrow-headed lines, passes between tension blocks 1 carried by a substantially built standard 2. It then goes over and under a number of rollers 3 which guide it through a body of coating fluid 4 in a container 5. A set of brushes or wipers 6 is arranged in this container well above the fluid body to remove any excess, the container being shaped to return this to prevent waste. Vertical rollers 7 are arranged at the container's exit portion for horizontal guidance of the strip. When a plurality of strips is being coated these 35 rollers serve to keep them separated.

An electrically heated baking oven 8 then receives the strip and hardens the coating fluid on it. Preferably, this is provided with a horizontal screen 8a located directly above its electric 40 heating elements. This screen functions to prevent a short circuit in case of strip breakage. This oven is supplied with a venting suction device 9 to remove any obnoxious fumes driven from the coating fluid by this heating.

The strip now passes through an open ended chamber 10 equipped with a blower fan 11 that creates a cooling current of air directed oppositely to the strip's travel. Just before it enters this chamber it is sponged by a set of absorbent rollers 12 which are arranged with their lower portions in a body of cooling fluid 13.

This cooling enables the application of wax to the strip when properly proportioned to the heat of the same upon entering the chamber 10, 10 which may be done by varying the speed of the blower fan, length of the strip's travel, or the cooling fluid's character.

Waxing is accomplished by a number of absorbent pads 14 supplied with a waxing medium 15 by an elevated supply tank 15 through a header 16 and spigots 17, the strip passing between these pads. The waxing medium mentioned may be a solution of paraffin and naphtha.

The strip is drawn through the various parts 20 of the apparatus by a pulling mechanism 18 and is finally wound in reel form by a take-up table arrangement 19, this final product having the desired finish. Preferably, a wipe 20 is arranged on the pulling mechanism 18 so that a final 25 smoothing or polishing is given the waxed strip.

This specific form of the new method and apparatus has been disclosed in accordance with the patent statutes and not as a limitation of the inventive scope, except as defined by the following.

We claim:

The method of protectively covering strip metal consisting in passing it through a body of coating fluid, wiping it free of any excess of this fluid 35 when entirely free from the body thereof, heating it to harden the fluid remaining thereon, sponging it with cooling fluid, passing it through a cooling chamber and waxing it as it leaves said chamber.
